FORMATION MODEL FOR RADIOACTIVE BOREHOLE LOGGING TOOLS

Dale H. Reed, William C. Pritchett, Robert D. Coffee,
Jack E. Hardison, and Carl A. Youngman, Dallas,
Tex., assignors to Atlantic Richfield Company, Phila-
delphia, Pa.

Filed Mar. 1, 1968, Ser. No. 10,803

Term of patent 14 years

Int. Cl. D10—11

U.S. Cl. D16—2

Fig. 2

Fig. 1

FIG. 1 is an isometric drawing of a formation model for radioactive borehole logging tools, embodying our design;

FIG. 2 is a side elevational view thereof.

We claim:

The ornamental design for a formation model for radioactive borehole logging tools, substantially as shown and described.
